UNITED STATES PATENT OFFICE.

LAURENCE S. LACHMAN, OF NEW YORK, N. Y., ASSIGNOR TO UNIVERSAL ELECTRIC
WELDING COMPANY, OF NEW YORK, N. Y., A CORPORATION OF NEW YORK.

POLE, &c.

1,235,332.

Specification of Letters Patent. Patented July 31, 1917.

Application filed October 19, 1910. Serial No. 587,794.

To all whom it may concern:

Be it known that I, LAURENCE S. LACHMAN, a citizen of the United States, and a resident of the city, county, and State of 5 New York, have invented certain new and useful Improvements in Poles, &c., of which the following is a specification.

This invention has relation to open-work or skeleton structures, such as are suitable 10 for use as poles for carrying, for example, telegraph wires, telephone wires, overhead-trolley wires, electric lighting wires, masts, staffs, columns, towers, beams, girders, concrete reinforcements, and a variety of other 15 purposes: its purpose being to provide an open-work or skeleton structure formed of metallic elements integrally united with each other, and having its elements so formed and disposed that the structure will have maximum strength while being comparatively 20 light, and may be most economically produced.

This purpose and others which will appear from the hereinafter description are 25 secured by the construction illustrated in the accompanying drawings to exemplify what is at present regarded as very desirable forms of the invention, but to the details of which the invention, in its broad 30 aspects, is not restricted.

In the drawings:

Figure 1 is an elevation of a structure embodying the present improvements.

Fig. 2 is a transverse sectional view on 35 the plane of the line 2—2 of Fig. 1, drawn on a larger scale than Fig. 1.

Fig. 3 is a view in transverse section, showing a slightly different structure embodying the present improvements.

40 Fig. 4 is a like view of another form of structure embodying the present improvements.

Fig. 5 is a like view of still a different structure embodying the present improvements.

45 Fig. 6 is a like view of another form of structure embodying the improvements.

Fig. 7 is a like view of a form whereof the structure of Fig. 5 is a unit instead of 50 the complete article.

Fig. 8 is a like view whereof the structure shown in Fig. 6 is a unit instead of the complete article.

55 Fig. 9 is a like view showing a structure composed of specifically different members

from those preceding, and embodying the present improvements.

Fig. 10 is a like view showing members substantially like those of Fig. 9, but differently arranged, in accordance with the 60 present invention.

Fig. 11 is an elevation of a structure embodying the specific form of elements shown in Fig. 9, said Fig. 9 being taken on line 9 of Fig. 11. 65

The same characters of reference designate the same parts in the several views.

The present structure comprises one or more longitudinal members, each having a plurality of portions which face in different 70 directions and are adapted for weldable union electrically with other members placed in contact therewith. These other members, in the various herein exemplified forms of the invention, form side members of the 75 structure, and they serve to connect the longitudinal members with each other, as exemplified by some of the herein illustrated forms, or they are connected with each other by a longitudinal member, as exemplified by 80 other illustrated forms, or both, as occasion requires.

The longitudinal member or members may be of various forms, and they may be variously arranged with respect to each 85 other and to the side members. The side members also may be variously arranged with relation to each other and to the longitudinal member or members and may be of various numbers or sizes, to accord with requirements of various structures which embody the present invention. Thus, for example, there may be a series of the side members on each side of the structure, and these members may be arranged transversely, diagonally, or both, of the structure, or otherwise as desired, within the broad 90 spirit of the invention.

Various forms of longitudinal members and various relative arrangements of longitudinal and side members are shown, but it is not intended to restrict the invention to these particular forms and arrangements, although they are preferred. 100

The illustrated forms of longitudinal members include a star-bar, marked 20 in all the forms where it appears, a T-bar, marked 30, wherever it appears, a Y-bar, marked 40 in all the forms showing it and a channel-bar, one suitable form of which is shown as 110

an example and is marked 50. Other forms of such members suitable for the purpose of the present invention will readily suggest themselves. The side members are marked 120 wherever they appear. In all of the herein exemplified forms of the invention a flat strip is suitable for weldable union with the longitudinal members, and as such strips are desirable for use in the present structures this form of side members is shown in all the accompanying figures of the drawings, though other forms may be employed, if preferred. In Fig. 1 a skeleton structure, rectangular in cross section, is shown as composed of a series of spaced side members on each of its sides, connected with each other by longitudinal members arranged in the angles of the structure. The side members are spaced apart along the length of the longitudinal members and the longitudinal members have separated welding places, hereinafter particularly described, at which they are integrally united to the side members by electric welds. These welding places on the side members face in different directions, each longitudinal member therefore being weldably united to the side members on two different sides of the structure. In this particular exemplification some of the side members, on each side of the structure, extend transversely of the structure while others extend diagonally and cross each other. The structure thus formed is comparatively light, may be inexpensively produced, and has the utmost strength and durability. Moreover, it may be easily transported and will withstand wind stress as well as all other strains and stresses to which it may be subjected in use. Again, the structure is such as to permit convenient access to the electrodes or terminals employed in the welding operation, to all of the intersecting portions, and the relative disposition of the members is such as to permit the structure to be supported by the table used in welding and to be moved along such table as the welding operation progresses. This materially contributes to the ease with which the structure may be formed and proportionately reduces the expense of such structure.

While the rectangular form of the structure is a desirable one, yet it may be of other cross sectional shape, including other forms of polygons as well as round or rounded shapes.

In the particular exemplification shown in Fig. 1, the longitudinal members are composed of star-bars 20. Upon reference to Fig. 2 it will be noted that the side members 120 are each weldably united to the edges 21 of two adjacent limbs of the star-bars, these edges forming welding places hereinbefore referred to. The star-bar provides channels between its limbs whereby

the welding places 21 are separated from each other, and the shape of the star-bar is such that its limbs face in different directions so as to present welding places 21 to side members arranged at an angle with each other. 70

The form exemplified in Fig. 3 is substantially like that already described, except that it employs T-bars in the angles of the structure, as the longitudinal members, instead of star-bars. 75

Fig. 4 shows a triangular structure whose longitudinal members are formed of Y-bars 40 arranged in the angle thereof and connected with each other by side members 120. 80

In Fig. 5 there is shown a rectangular structure wherein the body is formed of a star-bar 20 whose limbs extend of the corners of the structure and have their edges weldably united to the surface of the side members which are connected with each other, in this form, by said star-bar. 85

In Fig. 6 a triangular structure is shown, composed of a Y-bar 40 which extends longitudinally thereof, and the side members 120 are connected with each other by a Y-bar and have their surfaces welded to the edges of the latter. 90

In the form shown in Figs. 5 and 6, the members referred to form the complete structure, but, as exemplified by Figs. 7 and 8 they may form corners of structures, certain of the side members 120 being prolonged from one side to the other. 95

In Figs. 9 and 10, various relative arrangements of channel bars 50 with transverse members are exemplified. Thus in Fig. 9, the transverse members, 120, are disposed outside of the channel bars and the transverse bars are welded to the edges thereof, while in Fig. 10, the channel bars are outside the transverse members and the latter are welded to the surfaces thereof. 100

Obviously, it is not wholly essential to the invention considered in its broadest aspects that there be side members on all sides of the structure. 110

It will be apparent to those familiar with the art of electric welding that the relative dispositions and forms of the members herein described are such as to adapt the members to be weldably united with each other at their places of contact, and the mode of such welding, will, it is thought, be apparent also to such persons. Therefore it is believed to be unnecessary herein to explain the manner of producing the welds or to disclose the means therefor, further than to say that the contacting portions of the metal 115 are reduced to a plastic condition by an electric current passing therethrough, and the molecules are caused to coalesce by pressure, the means for producing this current of electricity and for applying it and pres- 120

sure to the members being such as are ordinarily employed in electric welding, or of any approved kind.

Attention is called to the fact that in each 5 of the herein illustrated embodiments of the invention there are separated welding places extending longitudinally of the longitudinal member and facing in different directions, their directions corresponding to 10 the different sides of the structure upon which the side members are disposed; and also to the fact that while the forms shown in Figs. 9 and 10 are specifically a form of channel bar, and have been so described herein- 15 in, yet the other illustrated forms also are such as substantially to provide channels extending longitudinally of the members between the limbs, and hence the term "channel" when used in the subjoined claims is em- 20 ployed in a full generic sense and unless otherwise defined, is not intended particularly to relate to the form which has hereinbefore been referred to as a "channel bar." The members 120 may be provided with 25 welding projections. These projections are shown on the horizontal members as continuous ridges which are marked *a*. The projections on the diagonal members are marked *b*. It is understood, of course, that these 30 projections rest against the vertical members and that said members are welded together by these projections.

Having thus described the invention what I believe to be new and desire to secure by 35 Letters Patent, is:

1. A corner connection for skeleton frame work, comprising a corner member and side members, the corner member having three or more radially extending limbs or flanges, 40 the side members being united to said limbs or flanges in pairs on contiguous sides of the corner member, each point of contact between the side members and corner member being a spot weld.

45 2. A structure comprising a plurality of longitudinal members and side members connecting the longitudinal members with each other, said members being relatively arranged to form a polygonal frame having

the longitudinal members in the angles 50 thereof and each of said longitudinal members having limbs which extend in different directions from a common center, the edges of the limbs being in contact respectively with the adjacent side members and electric 55 welds integrally uniting the contacting portions of the longitudinal and side members with each other.

3. A structure comprising a plurality of longitudinal members, side members connecting the longitudinal members with each other, said members being relatively arranged to form a polygonal frame having the longitudinal members in the angles 60 thereof, each of said longitudinal members having limbs which extend in different directions from a common center, two of the limbs being in the same plane, the edges of the limbs being in contact respectively with the adjacent side members, and electric welds 65 integrally uniting the contacting portions of the longitudinal side members with each other.

4. A structure comprising a plurality of longitudinal members, side members connecting the longitudinal members with each other, said members being relatively arranged to form a polygonal frame having the longitudinal members in the angles 70 thereof, each of said longitudinal members having limbs which extend in different directions from a common center, the limbs being arranged to extend opposite each other and in the same plane with each other, the inner edges of the limbs being in contact re- 75 spectively with the adjacent side members, the outer edges of the limbs being in contact respectively with bars joining the same, and electric welds integrally uniting the contacting portions respectively with each other. 80

In witness whereof I have hereunto set my hand at New York, county of New York and State of New York, this 14th day of October, 1910.

LAURENCE S. LACHMAN.

In presence of—

EDWARD FULDA,
MARGARET KELLEY.
